UNITED STATES PATENT OFFICE.

WADE W. WILLIAMS, OF PROVIDENCE, RHODE ISLAND.

CUFF-PIN.

1,027,302.

Specification of Letters Patent.

Patented May 21, 1912.

Application filed December 21, 1909. Serial No. 534,305.

To all whom it may concern:

Be it known that I, WADE W. WILLIAMS, a citizen of the United States, residing at Providence, in the county of Providence and 5 State of Rhode Island, have invented certain new and useful Improvements in Cuff-Pins, of which the following is a specification, reference being had therein to the accompanying drawings.

10 Like reference letters indicate like parts. Figure 1 is a top plan view of the blank for the base plate, pin housing and pin catch, used in the construction of my improved cuff pin. Fig. 2 is a side elevation of the 15 same. Fig. 3 is a side elevation of the pin tongue forming a part of my said cuff pin. Fig. 4 is a perspective view of said pin tongue, especially showing the spring coils and the spring presser foot thereof. Fig. 20 5 is a view in side elevation of the pin tongue, as seen mounted in its housing, and the ornamental front of the cuff pin rolled over upon the base plate, said ornamental front, housing and base plate being shown 25 in central longitudinal section. Fig. 6 is a view in end elevation of said base plate and housing, with the pin tongue mounted in the housing, and also a sectional view of the 30 base plate and ornamental front of the cuff pin, as seen on line $z-z$ of Fig. 5. Fig. 7 is a view in side elevation of my improved cuff pin, with the pin tongue engaged with the pin catch, the ornamental front of the cuff pin being represented in central longitudinal 35 section.

My invention relates to the class of cuff pins, and it consists of the novel construction and combination of the several parts thereof, as hereinafter described and 40 claimed.

In the drawings a blank is shown in Fig. 1, which is used as a base plate, pin-tongue housing and pin catch, when the latter has been properly bent into form adapting it 45 to a practical use. This blank has an elongated, generally-elliptical (or other preferred) outline or shape, and has the following named integral parts—a body portion A, a housing B and a lateral projection 50 C. The projection C, at that outer edge thereof, which is perpendicular to the major axis of the body A and near the end thereof, has a prolongation D. A small recess E is formed on the opposite edge of the body A, 55 opposite to the projection C and its prolongation D. The housing B has a central

longitudinal opening or slot F, on that edge which is parallel to the body A.

The pin-tongue G is made of a tempered wire or stock and has at one end the pin point H. At its opposite end it has the spiral coils I and J, of which the coil I is a closed, circular spiral and the coil J is a half-closed spiral, the latter extending as a projection or foot, which serves as a 60 presser K and said presser or foot terminates with an elongated closed loop L, adapted to lie flat in the plane of the presser K at a right angle with the coils I and J.

The blank, shown in Figs. 1 and 2, is bent 65 into the form shown in Fig. 7. The projection C is bent to form the hood M, which has an opening N for the entrance of the pin point H. The prolongation D of the projection C, when the hood M has been 70 bent into form, lies within the recess E of the blank, with its end flush with the under surface of the body A, as illustrated in Figs. 4 and 7.

The housing B has the central longitudinal slot or opening F on its top, as already described, and the inner end of said slot forms a stop σ to limit the closing oscillation of the pin tongue G, and the outer end of said slot forms a stop ρ to limit the outward oscillation of the pin tongue, when the coils I, J, of the pin tongue have been mounted in the housing B, as shown in Figs. 5, 6 and 7. The slot or opening F lies a little to one side of the central longitudinal line of the housing B, as represented in Fig. 1. The coil I lies loosely alongside one side wall of the housing B with the portion n of the coil I wholly covered by the portion m of said housing. The coil J lies loosely 80 alongside the inner surface of the other side wall, and the shaft G extends loosely through the slot or opening F. The presser foot K and its loop L lie flatwise, and extend beneath the body A of the base plate, directed toward the pin catch or hood M.

The ornamental front of the cuff pin is designated as Q, and extends parallel to the base plate A, as shown in Figs. 5 and 7, with its peripheral edge rolled over upon the base plate A to cover the edge of the base plate, as illustrated at R. Thus the rolled edge R extends along over the entire peripheral edge of the base plate, except the recess E, and across the opening of 95 said recess. Thus the prolongation or projection D of the hood M is prevented from 100 105 110

displacement from the recess E. The rolled edge R also extends along and over that portion of the base plate contiguous to the sides of the housing B and holds all the 5 parts together. The presser foot K is loosely held between and is in contact with the inner surface of the base plate A and the inner surface of the ornamental front Q, as seen in Figs. 5 and 7, and the pin 10 tongue G, extending loosely through the slot F of the housing B, is capable of an oscillatory movement limited by the stops O and P of the housing B.

The normal position of the pin tongue G, 15 is that illustrated in Fig. 5, and then the angle formed between the parts G and K is the same as the angle of said parts shown in Fig. 3. When the pin tongue G is swung to engage the hooded pin catch M, as represented in Fig. 7, the angle between the parts G and K is greatly reduced, and consequently these parts are put into spring tension. The result is that the pin point H is securely held in engagement with the 20 pin catch, and when released from such engagement, the pin tongue automatically opens to its normal position, seen in Fig. 5.

The pin tongue G and its integral coils I, J, presser foot K, and loop L are prevented 25 from lateral oscillation or rocking principally by the loop L of the presser foot K, which extends between the parallel, contiguous surfaces of the base plate A and ornamental front Q of the cuff pin, aided, however, to some degree, by the parallel side 30 walls of the housing B. The pin tongue stands upon its presser foot K, L, and is supported and prevented thereby from all lateral movement, the same result being aided 35 by the side walls of the housing B. The spring action of the pin in closing is due first to the resiliency of the presser foot K, L, until the shaft G comes into contact with the cross edge O of the slot F of the housing B. Said edge O then serves as a fulcrum 40 on which the shaft of the pin tongue G is sprung in the well-known manner. It is thus seen that the usual pivoting of the pin tongue to a pin joint is avoided and that 45 the usual resiliency of the pin tongue is enhanced, not only by the spiral coils, but especially by the spring temper of the looped presser or foot K, L.

If the stock from which the blank of the 50 base plate and its integral parts is formed is gold-plated stock, it is desirable that the

exposed surfaces of the pin catch or hood should be gold, instead of base metal.

This device is useful not only in the manufacture of cuff pins, but also in brooches 60 and similar articles.

The portion m of the housing B, as seen in Fig. 6, extends farther from the base plate than the transversely-opposite portions of the said housing and leaves an intermediate shoulder. This portion m not only 65 serves to cover and conceal the closed spiral coil I of the pin tongue G, but it protects the lace or other fabric of the cuff from becoming entangled between the coils I and J. 70

Instead of making the base plate with a pin-catch and housing both integral therewith, it is obvious that the base plate may be divided transversely along its minor axis, and the housing be integral with one part 75 of the base plate and the pin catch with the other part.

I claim as a novel and useful invention and desire to secure by Letters Patent:—

1. In a cuff pin or similar article, the 80 combination of a base plate having a pin catch, a housing having two parallel side walls and an open top, and also having two opposite end walls, a tempered pin tongue comprising all in one piece a shaft having 85 a pointed end, a presser at the opposite end and an intermediate spiral coil consisting of one full coil and one half coil, one of said side walls being extended farther from the base plate than the other and forming a 90 shoulder adapted to overlie said coil, an ornamental front, between which and the base plate said presser has a bearing, said pin tongue being loosely mounted in said housing by its spiral coils, and the shaft of 95 the pin tongue being capable of a longitudinal oscillation through said open top of the housing into engagement at its pointed end with the pin catch.

2. A hinge for cuff pins comprising a 100 housing having two parallel side walls, two opposite end walls and an open top, one of said side walls being extended farther than the other and forming a side overlying shoulder at the top of the housing and bordering the opening therein.

In testimony whereof I affix my signature in presence of two witnesses.

WADE W. WILLIAMS.
